UNITED STATES PATENT OFFICE.

CHRISTOPHER C. ROBBINS, OF PORTLAND, OREGON.

FASTENER.

Application filed March 1, 1928. Serial No. 258,263.

My invention relates to fasteners as a class.

The object of my invention is to provide a fastener of a bolt type, which may be installed and used for window sash and doors. The bolt is constructed without the common type of threading, tapping, screws, rivets or springs, and may serve both as a sash fastener and a lift. It is easily and quickly placed in operative position in new or old sash, without weakening the same, and will secure them so as to obviate play, as well as operating for an effective fastener. These objects, as well as other advantages, I attain by the construction, combination and arrangement of parts illustrated in the accompanying drawings which form a part hereof.

Fig. I is a front elevation of the device placed in operative position in sash stiles, partly shown.

Fig. II is a sectional view of the bolt with fastening latch in the handle thereof, as on line II—II in Fig. I.

Fig. III is a plan view of the device with the fastening latch in the handle.

Fig. IV is a front elevation of the bolt showing central groove to receive the handle with fastening latch.

Fig. V is a detail of the handle showing long vertical slot to receive the fastening latch.

Fig. VI is a detail view of the fastening latch.

Fig. VII is a plan view of the device with handle on the bolt, and fastening latch omitted.

Fig. VIII is a front elevation of the handle appearing in Fig. VII.

Fig. IX is a detail of the handle as secured upon the bolt shown in Fig. VII.

Like characters refer to like parts in the views.

In Fig. I is shown a window frame 1, one side of an upper sash 2 and lower sash 3 with the device installed in each sash, and showing in dotted lines the recesses 4 to receive the bolt. Metal sleeves 5 may be driven into the recesses to protect the adjacent wood. A horizontal opening 6 is bored in the stile of either sash. A transverse opening 7 is bored in the stile centered on the opening 6. Such an opening is seen in Fig. II. The fastener consists of a bolt 8. It is slightly tapered on one end, which allows it to enter the receiving recess without catching on adjacent parts. The handle

is made with a short or long longitudinal slot therein. The handle 9 has the short slot 10. It has a transverse opening 10^a through the slotted parts, allowing the bolt 8 to be driven through it. In this case the bolt is corrugated at 11 and the slotted part of the handle is spread in order to cause it to grip the bolt rigidly, as shown in Fig. IX. The handle 12 has a long slot 13. This handle has a transverse opening 14 and the bolt on which it is placed has a central groove 15. A fastening latch 16 is inserted in the handle slot 13. This latch has a transverse opening 17. In this case the handle is positioned in the opening 7 and the bolt 8 driven through the openings 14 and 17. These openings are flush with the surface of the bolt so that when the handle and latch are driven to a position in the groove 15 they drop into it and are easily movable therein. An escutcheon 18 is inserted in the opening 7 when the bolt and handle are in place. The escutcheon has a recess 18^a. The escutcheon 18 has a horizontal slot 19 through which the bolt handles extend outwardly and sufficiently to permit them to be grasped to move the bolt. In the case of the handle 12 the escutcheon 18 has a small slot 20 in the lower edge of its horizontal slot. This slot 20 is adapted to receive the fastening latch 16 and hold the bolt through the handle from being moved in either direction.

The operation of the bolts is clearly apparent from the illustrations. If desired, another latch slot may be made in the escutcheon. The slots should of course be positioned according to the use of the fastener. For instance, on windows there would be one latch slot only to prevent operation of the bolt from the outside. On doors the latch slot might be positioned for a hold open function. The construction of the escutcheon adapts it to serve also as a lift. The bolt end being pointed, when the bolt is in operative position a light tap thereon will accurately locate the bolt hole and by thus being self-centering, errors in construction are avoided. The method of attaching the handle to the bolt allows use of a bolt of small diameter and this will reduce movement friction to a minimum. The device may be installed in sash or doors without removal of any part thereof or marring the finish. Only two bored holes are required for complete installation and the device may

be used on very narrow and thin stiles. The device is ornamental and when fastened is invisible from the exterior. This bolt may be installed without exact alignment or position of parts. That is to say, the bolt may be set at varying depths in the stile or it may be slightly above or below the center of the escutcheon slot without impairing its operation. The device also tends to prevent the annoying rattle in loosely fitted windows. No change in detail from regular standards is required for its reception. An outstanding advantage of the device is that windows may be fastened with the sashes partly open. The top sash may thus be down a few inches and the lower sash raised a few inches and the bolts cannot then be tampered with from the outside, as they cannot then be reached and operated. It will further be observed that the fastener being installed in the lower part of the upper sash, that sash might be lowered with an opening of one foot at the top and the lower sash might be raised a few inches, and the lower sash would then cover the fasteners in the upper sash. In this position the upper fasteners would be inaccessible and the lower fasteners could not be reached through the lower opening and both operated at the same time. The construction is so simple that my fastener can be manufactured at a very low cost. Its cheapness and effective operation characterize its novelty and utility.

I claim:

35 1. In a device of the character described the combination of; a bolt handle having a longitudinal slot therein of convenient length and a transverse opening near one end, and a thin fastening latch having an opening 40 through one end positioned in alignment with the handle opening, said latch being adapted to be inserted in the handle slot

and the handle and latch being adapted to receive through their aligned openings a bolt and to oscillate thereon. 45

2. In a device of the character described the combination of; a bolt slightly tapered at one end and having a circular groove in its central portion, a handle having a longitudinal slot therein of convenient length and a transverse opening near one end adapted to receive the bolt therein and to allow the handle to oscillate in the bolt groove when positioned therein, and a thin fastening latch having an opening through one end, 50 said latch being adapted to be inserted in the handle slot and to receive the bolt through its opening in alignment with the handle opening and to oscillate upon the bolt in its grooved portion. 55

3. In a device of the character described the combination of; a bolt slightly tapered at one end and having a circular groove in its central portion, a handle having a longitudinal slot therein of convenient length and a transverse opening near one end adapted to receive the bolt therein and to allow the handle to oscillate in the bolt groove when positioned therein, a thin fastening latch having an opening through one end, 60 said latch being adapted to be inserted in the handle slot and to receive the bolt through its opening in alignment with the handle opening and to oscillate upon the bolt in its grooved portion, and an escutcheon having a recess therein and a slot adapted to receive the handle and fastening latch through the same, said escutcheon also having a small transverse slot in one edge of the slot first described, said small slot being 65 adapted to receive therein the fastening latch. 70
